UNITED STATES PATENT OFFICE.

JOHN A. EARHUFF, OF LOS ANGELES, CALIFORNIA.

SHOCK-ABSORBER FOR TYPE-WRITERS.

1,257,822.

Specification of Letters Patent. Patented Feb. 26, 1918.

Application filed May 24, 1917. Serial No. 170,753.

To all whom it may concern:

Be it known that I, JOHN A. EARHUFF, a citizen of the United States, residing at Los Angeles, in the county of Los Angeles and State of California, have invented a new and useful Shock-Absorber for Type-Writers, of which the following is a specification.

The present invention relates to a supporting base or stand for typewriters, and aims to provide a device of that character of such construction as to absorb the shocks and deaden the noise of the typewriter.

It is also the object of the invention to provide such a device which is extremely simple and inexpensive in construction, being readily manufactured cheaply from strips of metal, and being foldable for compact shipment or storage, as well as being adjustable to accommodate various typewriters.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:—

Figure 1 is a perspective view of the device.

Fig. 2 is a plan view thereof in folded position.

Figs. 3, 4 and 5 are sectional details on the respective lines 3—3, 4—4 and 5—5 of Fig. 1.

In carrying out the invention, there is provided a pair of supporting bars or strips 1 constructed of resilient material, and having their terminals bent back downwardly to provide feet 2 and resilient loops between said feet and the body portions of the bars 1, whereby the feet in being supported on the table or other support, will permit the bars 1 to yield and therefore absorb the shocks to which the typewriter, which is supported by the bars 1, is subjected.

In order to adjustably connect the bars 1 and permit them to be adjusted toward and

away from one another to accommodate various typewriters, and to permit the bars 55 to be brought together to fold the device, short links 3 are pivoted by means of screws 4 or otherwise upon the feet or terminals 2 of the bars 1 and relatively long crossed links 5 have their ends pivoted, as at 6, to 60 the other ends of the short links 3, and the links 5 where they cross one another at the intermediate portions thereof are also pivoted together, as at 7. The links 3 and 5 provide a modified form of lazy tong connection between the bars 1, to enable said bars to be moved toward and away from one another, and to be brought together, as seen in Fig. 2, in which position of the parts, the short links 3 swing over the feet 2 within the 70 loops of the bars 1, and the links 5 swing between the links 3 and bars 1.

Convexed washers 8 are disposed upon the screws 4, said screws having their heads 75 lowermost below said washers and their threaded ends engaging the links 3, and felt or other suitable pads or cushions 9 are seated in the washers 8 and are secured therein by the screws 4, as seen in Fig. 5. These pads 9 seat upon the table or other 80 support, and serve to cushion the shocks and prevent the device from slipping. The feet 2 are thus supported by the pads 9 above the surface of the table, thus permitting said feet 2 and loops of the bars 1 to spring. 85

Mounted upon the bars 1 are the cups 10 and 11 for receiving and holding ordinary rubber cushions or feet of the typewriter. The cups 10 at one end of the present device or frame are mounted slidably upon the 90 bars 1 for purpose of adjustment, and for this reason they are secured upon clips or slides 12 movable upon the bars 1. The cups 11 are secured rigidly upon the bars 1 at the other end of the frame, by means of screws 95 13 engaged downwardly through the bottoms of the cups 11 and threadedly engaging the bars 1. Cushions 14 of felt or other suitable material are disposed in the cups 10 and 11 to further cushion the shocks, and 100 the cushions 14 and cups 11 are held therein underneath the heads of the screws 13.

The bars 1 can be readily adjusted to bring the cups 10—11 at the opposite sides into the proper line, and the cups 10 can be 105 shifted on the bars 1, whereby all of the cups

are in position to be engaged by the pads or feet of the typewriter.

Having thus described the invention, what is claimed as new is:—

- 5 A supporting base for typewriters including parallel resilient bars having downwardly and inwardly turned terminals constituting yieldable feet, cushions carried by and depending from said feet, means upon
10 each bar and adjustable relative to each other upon the bar for engaging and holding

the typewriter, crossed pivotally connected links between the bars, and short link connections between said crossed links and the respective feet.

In testimony that I claim the foregoing as my own, I have hereto affixed my signature in the presence of two witnesses.

JOHN A. EARHUFF.

Witnesses:

EDNA G. EARHUFF,
E. F. SMITH.
